ADAPTER FOR ELECTRIC LAMPS

Mazeppa Don Betts, Rockport, Mass., assignor to
Sylvania Electric Products Inc., Salem, Mass.,
a corporation of Massachusetts

Application December 28, 1946, Serial No. 719,033

2 Claims. (Cl. 176—32)

1

This invention relates to bases for electric lamps and the like and more particularly to a base and adapter for a fluorescent Christmas tree lamp.

An object of this invention is to provide a base and adapter for a fluorescent Christmas tree lamp.

Another object is to provide an adapter for a fluorescent Christmas tree lamp to which a base can be securely attached.

A further object is to provide an adapter for a fluorescent Christmas tree lamp which can be securely attached to the lamp bulb.

A further object is to provide a base and adapter which can be readily assembled and attached to a fluorescent Christmas tree lamp.

A further object is to provide an electrically shock-proof base for a lamp.

Further objects, advantages and features will be apparent from the following specification and drawing in which:

Figure 1 is a perspective view of a fluorescent Christmas tree lamp bulb with the base and adapter of my invention attached thereto.

Figure 2 is an exploded view partly in section of one modification of my invention.

Figure 3 is an exploded view partly in section of another modification of my invention.

Figure 4 is an enlarged sectional view of the lower portion of the adapter of Figure 2, showing the manner in which the eyelet is seated.

In the manufacture of ornamental fluorescent lamps, such as Christmas tree lamps, for example, it has been found desirable in some cases to use a substantially spherical bulb. It has been found that when a bulb of this contour is used it is not practically possible to base it with a conventional candelabra or intermediate incandescent lamp base because the diameter of the neck of the bulb is too great. To overcome this difficulty I have developed an adapter which may be securely attached to the bulb and to which a base or shell may be connected.

In Figure 1 the bulb 1 is provided with an adapter 2 secured thereto and a metallic shell 3 is secured to the adapter. The lower end of the adapter 2 is provided with an eyelet 4. The adapter-shell assembly of Figure 1 is shown in detail in Figure 2. The upper portion of the adapter 2 of insulating material consists of a cup 5 which is designed to encircle and engage the neck of the bulb 1 and the lower portion of the adapter consists of a sleeve 6 to which the metallic shell 3 may be connected. The interior of the cup 5 is provided with an annular ring

2

7 and four ribs 8 to impart a mechanical locking of the adapter to basing cement which may be used to securely connect the adapter to the bulb 1. The upper portion of the sleeve 6 is provided with a plurality of elongated slots 9 disposed along the longitudinal axis of the sleeve 6 and extending downwardly from the bottom of the cup 5 terminating in a plurality of holes 10. The metallic shell 3 may be secured to the sleeve 6 10 of the adapter by crimping the deformed portions of the shell extending through the holes 10. The lower end of the sleeve 6 of the adapter is provided with an eyelet 4.

In the modification shown in Figure 3, the adapter 11 is characterized by substantially the same structural features described above with reference to the adapter 2 of Figures 1 and 2. In this modification a conventional base 12 may be employed instead of a metallic shell. Since 20 the conventional base is provided with an insulated eyelet in the bottom thereof, the adapter 11 of Figure 3 differs from the adapter 2 of Figure 2 in that it is not provided with a metal eyelet at the lower end thereof.

25 Although the adapter may be secured to the bulb and then the shell or base secured to the adapter, I have found it more convenient to mount the shell or base on the adapter and then secure the adapter to the bulb. In the modification shown in Figure 2, the shell 3 may be secured to the sleeve 6 of the adapter by crimping as described above or basing cement may be used. In some cases it may be desirable to employ both means. If desired the lower portion of the sleeve 35 6 may be externally threaded and the shell 3 screwed thereon. With reference to the modification shown in Figure 3, the several means or any combination of them, described above with reference to securing the shell 3 to the adapter 40 2, may be employed to secure the base 12 to the adapter 11.

After the base or shell has been secured to the adapter, the adapter is secured to the bulb 1. In performing this operation the lead-wires which 45 extend out of the bulb 1 from the electrode assembly are directed into the adapter. One of these lead-wires is threaded through one of the crimping holes 10. That portion of the lead-wire which extends out of the adapter through the 50 crimping hole 10 is severed and solder is applied to the crimping hole to establish the side electrical contact. In the modification shown in Figures 1 and 2 the bottom electrical contact is made by applying solder to the eyelet 4 after that 55 portion of the lead-wire which extends beyond

the bottom of the adapter has been severed. In the modification shown in Figure 3, the bottom electrical contact is established in a similar manner. The adapter may be secured to the bulb 1 by basing cement in the conventional manner.

The outer face of the adapter 2 of Figures 1 and 2 and the adapter 11 of Figure 3 is provided with guide slots 13 which aid in orienting the parts during the assembling operations. Although these guide slots have proven advantageous, I have also found that the elongated slots 9 can also serve as an internal orienting means.

What I claim is:

1. An adapter for electric lamps comprising a cup-like member having an annular raised portion about its inner wall intermediate the rim and the bottom thereof and a plurality of ribs disposed about the bottom thereof; and a sleeve member connected to the bottom of said cup-like member, said sleeve member being provided at its upper end adjacent the cup-like member with a plurality of elongated channels extending along its longitudinal axis, the lower portion of said channels terminating in apertures in the wall of said sleeve.

10
15

2. An adapter for electric lamps comprising a cup-like member having an annular raised portion about its inner wall intermediate the rim and the bottom thereof and a plurality of ribs disposed about the bottom thereof; a sleeve member connected to the bottom of said cup-like member, said sleeve member being provided at its upper end adjacent the cup-like member with a plurality of elongated channels extending along its longitudinal axis, the lower portion of said channels terminating in apertures in the wall of said sleeve; and an eyelet in the bottom of said sleeve.
